DIPPER TEETH

Robert G. Frye, Columbus, Ohio

Application June 22, 1948, Serial No. 34,381

8 Claims. (Cl. 37—142)

1

My invention as disclosed in this application relates to improvements in steam shovels. Specifically it relates to an improved type of digging means such as teeth adapted to be secured to the dipper bucket of such steam shovels and such as attachments or appliances designed to be secured to or used with steam shovel teeth in order to modify the action of the teeth and to produce a greater efficiency than has been heretofore possible.

One of the objects of my invention is an increase in the efficiency of steam shovels.

A further object of my invention is the provision of an improved design of a dipper bucket for steam shovels and of teeth and attachments therefor which will increase the efficiency of such steam shovels.

A further more specific object of my invention is the provision of means whereby a greater amount of stones, gravel, dirt, etc. may be forced into the bucket of a steam shovel and lifted thereby with the same amount of power or equal amount of stones, dirt, etc. forced into and raised with a smaller amount of power.

A further object of my invention is the provision of a dipper bucket equipped with dipper teeth having between the teeth a trough formed with turning side walls by which the stones are forced sideways so as to turn on a rolling surface and improve the efficiency of the digging operation.

Thus my improvements are specially desirable in the handling of stones inasmuch as by means of the improvements, the stones are caused to turn and act as rollers or bearings with the relatively greater efficient handling of such stones.

An even more specific feature of my invention is the provision of integral dipper teeth for steam shovels so formed that they cooperate with adjacent teeth to form a trough equipped with turning side walls for the efficient handling of stones, gravel, dirt, etc.

A further specific feature of my invention is the provision of a separate trough which may be secured between two adjacent teeth so as to form means for the more efficient handling of stones.

A further specific feature of my invention is the provision of a dipper front formed with troughs between which dipper teeth may be inserted so as to utilize more efficiently the digging capacity of such teeth.

Further objects and advantages of my invention will be apparent from the following description, reference being had to the accompany-

2

ing drawings wherein preferred forms of embodiments of the invention are clearly shown.

In the drawings:

Fig. 1 is a view in elevation of a steam shovel dipper bucket in the position which it assumes when the bucket is lifted after being filled with stones, dirt, etc.;

Fig. 2 is a view in perspective of one of the teeth shown in Fig. 1;

Fig. 3 is a view in horizontal section taken substantially on the line 3—3 of Fig. 1;

Fig. 4 is a view in horizontal section taken substantially on the line 4—4 of Fig. 1;

Fig. 5 is a view in top plan of one of the teeth looking at it from the digging edge;

Fig. 6 is a view in elevation of one of the teeth shown in Fig. 1 the tooth being inverted;

Fig. 7 is a fragmentary view in perspective showing diagrammatically several stones in the attitudes which they assume by reason of the trough and slot formed by two adjacent teeth in my improved dipper front;

Fig. 8 is a fragmentary view in elevation of a modified form of dipper front, teeth, and trough constructed in accordance with my invention;

Fig. 9 is a view in horizontal section taken substantially as if on the line 9—9 of Fig. 8;

Fig. 10 is a view in perspective of one of the teeth in Fig. 8;

Fig. 11 is a view in perspective of the trough element shown in Fig. 8; and

Fig. 12 is a fragmentary view in elevation of a further modified form of dipper front and tooth also constructed in accordance with my invention.

Referring again to the drawings for a detailed description of my invention, it may be seen that I have shown in Fig. 1 a dipper bucket 21 provided with teeth 22, 23, 24, 25 and 26. These teeth are formed or equipped with means to provide a trough having turning side walls. Thus the end teeth 22 and 26 are each provided with an inner side projection such as projections 27 and 28 and the intermediate teeth 23, 24 and 25 are each provided with a pair of side projections such as 29, 31, 32, 33, 34 and 35. As appears more clearly in Figs. 3 and 4, the projections 29, 31, 32, 33, etc. are separate from the teeth 23 and 24 but are secured thereto as by welding or by any other means for securely fastening the projections to the teeth. Preferably, however, the teeth are formed with integral projections such as the projections 34 and 35 of the tooth 25, shown in Fig. 6.

The shape and all details of the teeth 23 and 24 are the same as the tooth 25, except that in the latter the projections are integral while the teeth 23 and 24 have projections secured to the teeth as by welding. I prefer to secure the projections to the teeth by fuse welding. In practice, all teeth of any bucket would probably either have the projections all made integral or all have the projections separate but secured. I have shown the different forms of teeth on the same bucket merely for the purpose of illustration.

The shape of the turning trough is quite important. Referring especially to Fig. 6, it should be pointed out that the surfaces 36 and 37 of the projections 35 and 34 are in the same plane as the upper surface of the tooth 25 and in effect form a continuation thereof. The curved surfaces 38 and 39 curve downward and outward continuously in the shape somewhat of a plow. Therefore, between two of the adjacent projections as, for example, between the projections 21 and 29, there is thus formed the turning trough. The confronting edges of adjacent projections form a slot 41. Rearwardly extending keys such as 43, 44 and 45 (see Fig. 6) extend into the dipper front 42 to aid in solidly holding the teeth on the dipper. The front of each tooth is tapered or beveled as at 40 and 40a.

For further explanation of the taper I refer to Fig. 5. There the projections 29 and 31 have leading edges 50a and 50b, which are substantially continuations of the edge 50 of tooth 23, being in the same (horizontal as viewed in Fig. 5) plane therewith. The surfaces 36a and 37a of the projections 31 and 29 are continuations of and in the same plane as the upper surface of the tooth. The leading edges 50a and 50b are tapered into the surfaces 38a and 39a and into the plow-shaped surfaces 38a and 39a by the tapering surfaces 40b and 40c.

As is shown in Fig. 7, stones such as 46, 47, 48 and 49 when engaged by the plow-shaped turning side wall of the trough formed by the projection 33, are turned by operation of the side wall of the trough and the slot to positions in which they will roll so that not only are the stones themselves forced back more efficiently along the trough into the dipper, but also the stones themselves often serve as rollers (in the nature of roller bearings) for transporting larger stones which may happen to be placed above them.

In the arrangement shown in Figs. 8, 9, 10 and 11, the dipper front 61 has secured thereto a plurality of teeth such as 62 and 63 and between each pair of such teeth, there is a trough element such as 64 which is also secured to the dipper front 61 and which is shaped somewhat similarly to the trough formed by a pair of the projections shown in Figs. 1 to 7, inclusive. The trough 64 adjacent the leading edge has a pair of flat portions 65 and 66 which are in the plane of and form continuations of the upper surface of the teeth 62 and 63. The trough element 64 is also formed with curved (plow-shaped) surfaces which lead down to the actual line 67 of the trough and operate in the same way as the trough described in connection with Figs. 1 to 7, inclusive. As appears more clearly in Fig. 10, the tooth 62 is formed with a groove or slot 68 which fits over the dipper front 61 and by means of which the tooth 62 is secured to the front 61. Similarly the trough element 64 is formed with a groove or slot 69 which also fits over and secures the trough element to the dipper front. Thus the

dipper front has cooperating therewith a trough equipped with or having turning side walls.

In Fig. 12, a further modification is shown. Therein the trough elements 71, 72, 73, etc. are made integral with the dipper front 74. Teeth such as the tooth 75 fit over and are secured to the dipper front 74 in the same manner that teeth such as the teeth 62 and 63 fit over and are secured to the dipper front 61. It is to be understood that between each pair of adjacent trough elements and at each of the two sides, a dipper tooth is inserted so that dipper troughs are positioned between each pair of adjacent teeth. Such dipper troughs have turning side walls.

In the operation of a steam shovel equipped according to my invention, the bucket and dipper are operated in the usual way. However, when the teeth bite into the bank less frictional resistance is encountered because of the action of the stones, within the trough or runway which is equipped with turning side walls, the action being illustrated in Fig. 7. Thus it must be seen that if the stones are laying horizontal as shown by the stone 46, they become tipped by the plow action of the turning side walls as shown by the stone 47, 48 and 49 and by the cooperation therewith of the slot (e. g., the slot 41) until they are in a position in which they roll. Thus the rolling of the underneath stones not only eliminate a large part of their own friction but also enable the stones which are on top of them to roll over them, the action being in the nature of the action of roller bearings, I have found that I can by the use of this improvement dig more stones, gravel, dirt, etc. with the same amount of power or dig an equal amount of stones, gravel, dirt, etc. with less power. Moreover, in the dumping from the buckets of the material which has been gathered into such buckets, less of the materials spills out between the teeth than would spill out if there were no lateral projections between the teeth. In this way, less stones, gravel, etc. fall on the roadway on which the receiving truck or on the railway on which the receiving car is placed and work in clearing away this debris is thus minimized. The resistance of a straight front such as might be provided if the teeth were made solid across the dipper front or if the lateral projections between the teeth were made solid and of equal cross-section with the teeth, would be greater and thus not even as satisfactory as a dipper front equipped with separated teeth. However, my arrangement in which the troughs between the teeth have a smaller cross-section than the teeth themselves is such that much greater efficiency is obtained than is the case either with a solid front or separated teeth having no lateral projections.

While the forms of embodiments of the present invention as herein disclosed constitute preferred forms, it is to be understood that other forms might be adopted, all coming within the scope of the claims which follow.

65 I claim:

1. For use in combination with a power operated shovel, a dipper bucket having a plurality of teeth, each of said teeth being provided with a tapered projection extending outwardly from the side thereof, the projections of adjacent teeth cooperating to form a trough having turning side walls into and through which stones may pass and to form a slot between the projections of each pair of adjacent teeth, which slot cooperates with the turning side walls to turn such

stones to positions in which they will roll into and rearward from said trough.

2. For use in combination with a power operated shovel, a dipper bucket having a plurality of teeth, each of said teeth being provided with a tapered projection shaped like a plow and extending outwardly from the side thereof, the projections of adjacent teeth cooperating to form a trough with turning side walls into and through which stones may pass and to form a slot between the side walls of the trough, the trough and the slot cooperating with the turning side walls to turn such stones to positions in which they will roll in and rearward from said trough.

3. For use in combination with a power operated shovel, a dipper bucket having a plurality of teeth, each of said teeth being provided with a tapered projection extending outwardly from the side thereof and extending forward substantially to the front of the adjacent teeth but tapering rearwardly to form a notch, the projections of adjacent teeth cooperating to form a trough having turning side walls into and through which stones may pass and to form a slot between the side walls of each trough which cooperates with the trough and the taper of the projections to turn such stones to positions in which they will roll in and rearward from said trough, whereby friction of the stones is minimized, the notch being formed at substantially the center line of the trough.

4. For use in combination with a steam shovel, a dipper bucket having a plurality of teeth, said teeth being provided with a plurality of projections, each extending laterally from confronting sides of adjacent teeth and said projections cooperating to form a trough having tapered turning side walls between each pair of teeth and into and through which stones may pass, and the confronting edges of said projections being spaced from one another to form a slot in the trough between each pair of adjacent teeth which cooperates with the trough and the taper of the side walls to turn such stones to positions in which they will roll in and rearward from said trough, whereby friction of the stones is minimized.

5. For use in combination with the power operated shovel, a dipper bucket having a plurality of forwardly projecting teeth at the front thereof, said teeth being spaced from one another, each of said teeth being tapered upwardly rearwardly to gradual increased thickness in vertical cross section; substantially horizontal aggregate runway forming means between adjacent teeth including sections extending laterally from the confronting sides of adjacent teeth, each of said sections having a leading edge starting at the front edge of the tooth and extending rearwardly and laterally from the front edge of the tooth, each of the top surfaces of said sections declining from the tooth, from which it laterally projects, toward the next adjacent section of the next adjacent tooth.

6. For use in combination with the power op-

erated shovel, a dipper bucket having a plurality of forwardly projecting teeth at the front thereof, said teeth being spaced from one another, each of said teeth being tapered upwardly rearwardly to gradual increased thickness in vertical cross section; substantially horizontal aggregate runway forming means between adjacent teeth including sections extending laterally from the confronting sides of adjacent teeth, each of said sections having a leading edge starting at the front edge of the tooth and extending rearwardly and laterally from the front edge of the tooth, each of the top surfaces of said sections declining from the tooth, from which it laterally projects, toward the next adjacent section of the next adjacent tooth, the confronting edges of said sections being spaced from one another to form a rearwardly extending slot therebetween.

7. For use in combination with the power operated shovel, a dipper bucket having a plurality of forwardly projecting teeth at the front thereof, said teeth being spaced from one another, said teeth being tapered upwardly rearwardly to gradual increased thickness in vertical cross sections; a substantially horizontally extending trough between adjacent teeth including sections extending laterally from the confronting sides of adjacent teeth, each of said sections having a leading edge starting at the front edge of the tooth and extending rearwardly and laterally from the front edge of the tooth, each of the top surfaces of said sections declining from the tooth, from which it laterally projects, toward the next adjacent section of the next adjacent tooth.

8. For use in combination with the power operated shovel, a dipper bucket having a plurality of forwardly projecting teeth at the front thereof, said teeth being spaced from one another, said teeth being tapered upwardly rearwardly to gradual increased thickness in vertical cross sections; a substantially horizontally extending trough spanning adjacent teeth including connected sections, each of said sections extending laterally from the confronting sides of the adjacent teeth, each of said sections having a leading edge starting at the front edge of the tooth and extending rearwardly and laterally from the front edge of the tooth from which it laterally projects, each of the top surfaces of said sections declining, from the tooth from which it laterally projects, to the connecting section.
